UNITED STATES PATENT OFFICE.

EDWARD FINK, OF MILWAUKEE, WISCONSIN, ASSIGNOR OF ONE-HALF TO HALLECK W. SEAMAN, OF CLINTON, IOWA.

RETORT APPARATUS.

1,213,346.

Specification of Letters Patent.

Patented Jan. 23, 1917.

Application filed May 9, 1914. Serial No. 837,386.

To all whom it may concern:

Be it known that I, EDWARD FINK, a citizen of the United States, residing at Milwaukee, in the county of Milwaukee and State of Wisconsin, have invented certain new and useful Improvements in Retort Apparatus, of which the following is a specification, reference being had to the accompanying drawing, forming a part thereof.

This invention relates to retort apparatus for metallurgical operations and the objects of the invention are to improve retort apparatus in the manner to be hereinafter described and claimed.

Referring to the drawings which accompany this specification and form a part hereof, on which drawings the same reference characters are used to designate the same parts wherever they appear in each of the views, and which drawings illustrate an embodiment of this invention, Figure 1 is a vertical, longitudinal, sectional view of a metallurgical furnace taken on the line *a—a* 20 on Fig. 2; and Fig. 2 is a horizontal, sectional view of the furnace taken on the line *b—b* on Fig. 1.

Referring to the drawings, the reference numeral 1 designates a furnace structure 30 providing a combustion chamber 2 within which are located the retorts 3, 4, 5 and 6.

The furnace structure and its combustion chamber may be of any convenient and suitable size and may contain one retort or a plurality of retorts. I have illustrated four retorts simply as a matter of convenience in describing this invention and I have illustrated a furnace arranged to reduce zinc oxide to metallic zinc and shall describe the operation of reducing zinc oxide but by such illustration and description I do not intend to limit this invention to the treatment or reduction of zinc oxide as it will be readily understood that the retort apparatus illustrated and described can be used for reducing other metalliferous materials.

The retorts 3, 4, 5 and 6 are long, high and narrow and their length and height is limited only by the flame zone of the heating agent employed. If a coal fire is used the flame zone of combustion, with grates only at the front of the furnace, will be considerably less than when gas, oil or powdered fuel is used. I have illustrated burners 7,

8, 9, 10 and 11, conventionally, through 55 which gas, oil or powdered fuel may be supplied to the combustion chamber. For general use the retorts may have a length of sixteen feet and a height of eight feet but these dimensions may be increased or decreased to suit special operating conditions, as the only point to be guarded against is making the retorts so long or so high that they cannot be heated to the necessary temperature. I prefer that the interior width 60 of the retorts shall not exceed eight inches, the object being to have the retorts as narrow as possible while allowing plenty of space for the material under treatment and for the escape of the gases and vapors generated. The retorts should be constructed of highly refractory material which has great heat conducting capacity and preferably are built up with suitable brick such as 65 carborundum, magnesite, chrome or other 70 suitable fire brick. If only one retort were set in a combustion chamber, approximately half of the heat would be wasted by heating the walls of the combustion chamber, so I prefer to place a plurality of retorts in a 75 combustion chamber spaced apart so that 80 flues are formed between them whereby the retorts receive most of the heat. I also prefer that the tops of the retorts be spaced from the top of the combustion chamber so 85 that they will be more thoroughly heated and the bottoms of the retorts may be exposed to the heat also but the bottom areas of the retorts are so small that they can be built on a solid foundation, as illustrated by 90 the drawings, without impairing their efficiency and such a construction is conducive to rigidity and long service. The bottoms of the retorts may be inclined toward one 95 end and temporary, removable brick work 12 used to close an aperture affording access to the interior of each retort, an aperture in the furnace structure being also closed by 100 temporary, removable brick work 13.

The retorts are provided with feed pipes 100 14, 15, 16 and 17, which for zinc work should be long enough to condense zinc vapor, and these pipes are sealed by the material to be fed to the retorts which, being ordinarily in the form of powder, will seal 105 the retorts from the air on the outside and will prevent the escape of gases and zinc vapor. I prefer to effect this sealing of the

feed pipes by means of a hopper 18 and conveyer mechanism 19, illustrated by the drawings as an ordinary form of screw conveyer, a separate hopper and conveyer being provided for each feed pipe, as such a construction affords means for feeding material to the retorts either continuously or intermittently according to circumstances.

The flues between the retorts and between the side walls of the furnace and the adjacent retorts may be supplied with air to promote complete combustion by the ducts 20, 21, 22, 23 and 24. The air may be supplied by a blower 25 and the quantity regulated by dampers 26, 27, 28, 29 and 30. The waste products of combustion may be removed from the furnace in any suitable manner and I have illustrated two chimneys 31 and 32 provided with dampers 33 and 34 so that the hot products of combustion may be directed to one chimney or the other or equally or unequally divided between them whereby the uniformity of temperature within the furnace and combustion chamber can be more readily secured.

I shall now proceed to describe the special arrangements adopted for the reduction of zinc.

Each retort is provided with a zinc condenser 35, 36, 37 and 38 with the ordinary collecting bowl 39 and ladle and gas aperture 40. I inclose the ends of the condensers in chambers 41, 42, 43 and 44 which communicate with the combustion chamber 2 by flues 45 controlled by dampers 46, 47, 48 and 49. Access may be had to chambers 41, 42, 43 and 44 and to the condensers therein by means of doors 50, 51, 52 and 53 and products of combustion may escape through exit openings 54 which may be provided with removable covers 55. This construction enables me to control the temperature of each condenser and thereby secure the zinc in liquid form avoiding the formation of the so called "blue powder."

Each retort is provided with a reduction chamber 56 located in the combustion chamber 2 and between the retort and the condenser connected therewith. I prefer to form these reduction chambers as a part of the retort structures by building an apertured wall 57 across the rear end of the retort. A charging pipe 58, 59, 60 and 61 communicates with each reduction chamber 55 and these pipes are kept closed by covers 62.

In reducing zinc oxid, the reduction chambers are charged to a point above the retorts and condensers with coke or charcoal and the object of these reduction chambers is to arrest all fine dust generated during the feeding of the retorts and to reduce any oxids which may volatilize before being reduced by the reducing material which is charged to the retorts mixed with the ore. These reduction chambers aid greatly in

keeping the condensers free from dirt or dust, oxids, etc. and thereby facilitate the condensation of the zinc vapor.

To prevent loss and waste of zinc, the charging pipes 58, 59, 60 and 61 as well as 70 the feed pipes 14, 15, 16 and 17 should be long enough to condense zinc vapor to prevent the escape of zinc when these pipes are purposely or accidentally opened to the atmosphere.

The use and operation of the apparatus is as follows. The hoppers 18 are filled with a mixture of zinc oxid and carbon (coke or charcoal) and the conveyers 19 fill the retorts; the retorts being heated sufficiently, 80 the oxygen in the oxid unites with the carbon, the zinc distils over and condenses in the condensers from which it is ladled as frequently as necessary. The carbon mon-oxid formed by the reaction burns at the 85 apertures 40 and, if necessary, the doors 50, 51, 52 and 53 may be opened and the covers 55 removed to supply air to support this combustion. If the temperature of a condenser falls below the temperature necessary 90 for the condensation of the zinc, the damper controlling flue 45 may be opened to permit the hot products of combustion in combustion chamber 2 to enter the chamber in which the condenser is located to increase the 95 temperature of the condenser. As the carbon (coke, for example) in the reduction chambers 56 is consumed, more carbon is supplied through the charging pipes. The hoppers 18 are kept supplied with a mixture 100 of the oxid or ore and carbon and, preferably, the conveyer 19 for each retort is run at such a speed that it will charge fresh materials as fast as the reduction and distillation takes place, the retorts being kept filled 105 and the temperature not being materially reduced by the material fed.

It will be noticed that the retorts are formed with substantially rectangular outlines as this construction combines strength 110 with simplicity of construction and provides proper flue spaces between the retorts and between the retorts and the sides of the combustion chamber. These retorts can be used for the reduction of other metals than zinc, 115 as lead, for example, in which case the condensers will, of course, be omitted.

The advantages of the apparatus over the apparatus and methods now in use are many. The distilling operation can be conducted 120 continuously and with a great saving of fuel, labor and time as the retorts do not have to be cooled, dismantled and recharged as is the present practice. Four retorts of the sizes indicated as suitable for general use 125 will do the work of three hundred or more of the retorts now in use for the reduction of zinc. The construction is such that tight joints can be secured so that there will be no waste and loss of zinc by leakage. By con- 130

trolling the temperatures of the condensers liquid zinc is obtained and the bugbear of "blue powder" is eliminated. The reduction chambers keep the retorts clean and free of 5 dust and oxid.

What is claimed is:

1. A long, high and narrow retort of substantially rectangular outlines, in combination with means for heating the same, a condenser in communication therewith, the retort being provided with an upright feed pipe for feeding material to the retort and condensing metallic vapor arising from the retort thereinto, and means in communication with the feed pipe adapted to hold material to seal the interior of the retort from the air.
2. The combination with a furnace provided with a combustion chamber, of a plurality of long, high and narrow retorts of substantially rectangular outlines located in said combustion chamber and spaced apart to form flues therebetween, each of said retorts being provided with an upright feed pipe for feeding material to a retort and condensing metallic vapor arising from a retort thereinto, material holding means in communication with the feed pipes to seal

the interiors of the retorts from the air, and condensers in communication with the retorts.

3. The combination with a furnace provided with a combustion chamber, of a chamber adjacent thereto, a long, high and narrow retort in the combustion chamber, a condenser leading from said retort into the adjacent chamber and a flue for leading combustion products from the combustion chamber into the adjacent chamber for heating the condenser therein.

4. The combination with a combustion chamber of a long, high and narrow retort located therein and provided with a reduction chamber in communication therewith in the combustion chamber, a feed pipe for supplying material to the retort, a feed pipe for supplying material to the reduction chamber, and a condenser in communication with said retort through said reduction chamber.

In witness whereof I hereto affix my signature in presence of two witnesses.

EDWARD FINK.
